UNITED STATES PATENT OFFICE

2,265,577

SCISSORS SHARPENER

Howell J. Rains, Mansfield, La.

Application August 28, 1939; Serial No. 292,280

2 Claims. (Cl. 76—82.2)

This invention relates to a scissors sharpener.

An object of the invention is to provide a hand tool of the character described particularly constructed for use in sharpening the blades of scissors, although the tool may be used for sharpening any type of blade having a bevelled edge.

Another object of the invention is to provide a tool of the character described embodying a vise for gripping the blade to be sharpened and an adjustable guide, or support, for the whet stone or other stone which may be accurately adjusted into position such that the grinding or abrading surface of the stone will be at an angle corresponding exactly to the bevel of the blade to be sharpened.

The invention also embodies means for accomplishing the easy and exact adjustment of the support for the stone or file or other grinding implement to be used in sharpening the blade.

When the blade is inserted into the vise it must be adjusted lengthwise until the bevelled portion to be operated on is in exact parallel relation with the support for the grinding implement. The tool is provided with means for making an indicating mark on the blade when so adjusted and the tool is also provided with a pointer which will be opposite said mark when the same is formed so that when the blade is to be again sharpened it may be quickly and accurately located in the vise with the pointer opposite the mark on the blade which has been so made.

When the blade is properly adjusted in the vise and secured against movement therein the support for the grinding implement must then be adjusted so that when the grinding implement is resting on said support its grinding face in contact with the bevelled portion of the blade will be inclined so as to exactly fit said bevelled portion to accomplish a uniform grinding action throughout the bevelled area of the blade. For adjusting the support an adjusting screw is provided having a scale thereon so that when the support is once adjusted for a particular blade the scale can be noted and when said blade is again to be sharpened the adjustment of the support can be quickly and accurately made.

It is another object of the invention to provide a scissors sharpener of the character described which when properly adjusted will enable the user to quickly and easily apply the grinding implement or stone to the blade without danger of injury to the blade and may sharpen the

cutting edge from end to end thereof with little effort or attention.

With the above and other objects in view the invention has particular relation to certain novel features of construction, operation and arrangement of parts, an example of which is given in this specification and illustrated in the accompanying drawing, wherein:

Figure 1 shows a front elevation of the tool, partly in section.

Figure 2 shows an end elevation shown partly in section.

Figure 3 shows a plan view.

Figure 4 shows an elevational view of the movable jaw of the vise, and

Figure 5 shows a sectional view thereof taken on the line 5—5 of Figure 4.

Referring now more particularly to the drawing wherein like numerals of reference designate similar parts in each of the figures, the numeral 1 designates a frame of a general arcuate shape having an internally tapped bearing at one end and whose other end is widened and formed with an arcuate end notch 3 with the fixed clamp jaws 4, 4a one on each side of the notch 3a. Projecting forwardly from the widened end of the frame and arranged parallel are the ears 5, 5. Between these ears there is a U-shaped jaw member 6, the upper ends of whose side arms are provided with the movable clamp jaws 7, 7. The member 6 has the end pintels 8, 8 which rotate in suitable bearings as 9 in the ears 5. A clamp screw 10 is threaded through the frame 1 and its inner end bears against the lower end of the U-shaped member 6.

The blade to be sharpened may be inserted between the fixed and movable jaws as indicated in dotted lines in Figure 1, said blade resting on the shoulders 11, 12 and the clamp screw 10 then screwed inwardly to cause the jaws, forming the vise to securely grip the blade.

On the frame 1 there is an upwardly extended ear 13 and pivoted to this ear there is a forwardly extended arm 14 secured to the free end 45 of which there is an arcuate saddle 15 in which there is mounted a cylindrical support 16 preferably formed of glass. Before the blade is clamped in the vise it should be adjusted until the bevelled face on its edge is in exact parallel 50 relation with the support 16. In use the stone, file, or other implement used for sharpening the blade will lie on the support 16 and on the bevelled edge of the blade and consequently said support should be adjusted so that said sharpening implement will lie at the same angle as the

angle of the bevel as is indicated in dotted lines in Figure 2. This adjustment of the support 16 is accomplished by an adjusting screw 17 which is threaded through the tapped bearing 2 and whose upper end engages the underside of the free end of the arm 14 as shown in Figure 2. This adjusting screw 17 has a scale 18 on one side as shown.

When the blade has been adjusted to the proper position a mark should be made on said blade so that when it is again inserted into the sharpened and said mark is brought exactly opposite the pointer 19 the beveled edge will be in exact parallel relation with the support 16. In this manner the blade can be quickly adjusted in proper position in the vise.

For the purpose of making this mark on the blade a bracket 20 has been provided. As shown this bracket is mounted to rotate on the transversely aligned spindles 21, 21 which extend inwardly from the side arms of the jaw member 6 as shown in Figure 2. The bracket 20 is upwardly arched, and carries a pointed punch 22. One end of the bracket is formed square as shown in Figure 5 and a strong flat spring 23 is secured at its outer end to the jaw member 6 and its inner end is free and rests against one side of the square end of said bracket as shown in Figure 5. The bracket may be pulled backwardly, or away from the blade, when the blade is adjusted to the desired position, placing the spring 23 under tension and upon release of the bracket the pressure of the spring will force the punch 22 suddenly against the blade thus making the desired mark exactly opposite the pointer 19. The bracket may then be retracted into the position shown in dotted lines in Figure 4, the spring 23 yielding to permit this and the spring will then rest against the opposite side of the square end of the bracket to hold the bracket in said retracted or inactive position until it is desired to make another mark on the blade or until it is desired to mark the blade of another pair of scissors to be sharpened.

At times it is desirable to use a polishing rod

for smoothing up the edge of a blade. This polishing rod is used in the same manner as the stone or file as hereinabove explained. For convenience the support 16 may be made hollow and the polishing rod as 24 for convenience may be kept therein and retained against accidental displacement by means of a retainer 25 which may be normally held closed by a suitable spring 26.

The drawing and description are illustrative merely, while the broad principle of the invention will be defined by the appended claims.

What I claim is:

1. A blade sharpener comprising an arcuate frame having spaced clamp jaws at one end, spaced clamp jaws pivoted to said end of the frame and arranged to cooperate with the fixed jaws to clamp a blade between them, a clamp screw threaded to the frame for actuating the pivoted jaws into clamping relation with a blade between the pivoted jaws and the fixed jaws and for releasing the pivoted jaws from the blade, a forwardly extended arm pivoted to the frame, an arcuate saddle on the free end of said arm, a support for a sharpening implement on the saddle and an adjusting screw threaded to the frame and forming means for adjusting said arm on the frame.

2. A blade sharpener comprising a frame having a fixed clamp jaw at one end, a clamp jaw pivoted to said end of the frame and arranged to cooperate with the fixed jaw to clamp a blade between them, a clamp screw having a threaded connection with the frame for actuating the pivoted jaw into clamping relation with a blade between the jaws and for releasing the pivoted jaw from the blade, a forwardly extended arm pivoted to the frame, an arcuate saddle on the free end of said arm, a cylindrical support for a sharpening implement on the saddle and an adjusting screw having a threaded connection with the frame and engageable with the arm for adjusting said arm and support relative to the frame.

HOWELL J. RAINS.
